UNITED STATES PATENT OFFICE.

WALTER G. HUMPHREYS AND OMAR R. HUMPHREYS, OF OMAHA, NEBRASKA.

PULLEY STRUCTURE FOR TRENCH-FILLING MACHINES.

Application filed November 3, 1924. Serial No. 747,611.

To all whom it may concern:

Be it known that we, WALTER G. HUMPHREYS and OMAR R. HUMPHREYS, citizens of the United States, residing at Omaha, in the county of Douglas and State of Nebraska, have invented certain new and useful Improvements in Pulley Structures for Trench-Filling Machines, of which the following is a specification.

The present invention relates to trench filling machines and has more particular reference to a pulley structure and mounting thereof for facilitating the operation of the machine.

An object of the invention is to provide a pulley which is counterweighted and pivoted so that it may follow the direction of pull upon the cable which is trained over the pulley and thus offer the least resistance to action during the operation of the machine, and to also maintain the cable from drawing over the top of the pulley.

Another object of the invention is to provide an improved mounting for the counterweighted pulley on the end of a boom so that the boom may be swung transversely of the machine and may also be raised and lowered and at the same time maintain the pulley in proper working position during these adjustments of the boom.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of the forward portion of a trench filling machine having the devices of this invention applied thereto.

Figure 2 is a top plan view of the same.

Figure 3 is a fragmentary front elevation of the machine showing a scraper or shovel connected to the parts, and

Figure 4 is an enlarged detail sectional view taken longitudinally through one of the counterweighted pulleys on its pivotal support.

Referring to the drawings 10 designates the work frame of a trench filling machine which may be of any suitable construction and which is provided with an upright 11 provided at its top with a pulley 12.

The frame 10 carries a boom 13 which is

pivoted upon the upper end of a bearing 14 carried on a large gear wheel 15 arranged horizontally in the frame 10 and operated in any suitable manner as by a worm 16 on a shaft 17. The frame may be supported upon wheels 18 and it is provided at its forward end with a cross piece 19 to which is secured an out rigger 20 the latter projecting from one forward corner of the frame as shown to advantage in Figure 2.

The out rigger 20 is provided with a pivot bracket 21 upon its outer extremity and the bracket forms an elongation of the out rigger and is arranged to support a pulley frame 22 forked at one end and in which is mounted a pulley 23 while the other end 24 of the frame 22 provides a weight arm which may be constructed of suitable thickness to provide the necessary counterweight for the pulley 23 and the parts bearing on the same, or which may be weighted in any other suitable manner.

The boom 13 has an outer end portion 25 forming an extension for the boom and the latter may be projected to various extents and secured in adjusted position by a pin 26 adapted to engage in openings 27 formed in the extension 25 and the boom 13 and adapted to register at various adjustments of the extension 25.

The outer end of the extension 25 is provided with a laterally extending head 28 which is connected in any suitable manner to the extension 25 and which forms a link or connecting portion between the outer end of the boom and an adjusting cable 29 which is connected to the link 28 and is carried backwardly and trained over the pulley 12 at the top of the post or standard 11. It will be noted from Figures 1, 2 and 3 that this head 28 extends not only upwardly and rearwardly from the end of the boom 13 but that it also is inclined laterally therefrom so as to dispose the cable 29 in such position that it may exert a direct pull upon the outer end of the boom irrespective of the transverse location of the outer end of the same.

The head 28 is provided with an outstanding pin 30 forming a pivot for a second counterweighted pulley frame 22 in which is disposed a second pulley 23 and which has the weight arm 24 as above described. The pin 30 is off set from the axis of the extension 25 of the boom and in such posi-

tion that the pulley 23 may clear the end of the boom and permit of the vertical and transverse adjustment of the head 28.

A shovel 31, scoop or other suitable device is connected at one end to one end of a cable 32 which is carried over the pulley 23 mounted on the head 28, and said cable 32 may be connected to any suitable mechanism for drawing the cable 32 and for paying the same out as the shovel 31 is moved back and forth across the front of the work frame 10. The other end of the shovel 31 is connected to another cable 33 which is trained over the pulley 32 carried upon the out rigger 20 and the cable 33 may be passed over guide pulleys 34 which are mounted upon the forward end of the frame 10 and operated by any suitable mechanism for drawing in and paying out the cable 33 or alternate operation for moving the shovel 31 back and forth.

As the pulley frames 22 have the counterweights 24 the pulleys are held in line with their respective cables 32 and 33 by the draft on the cables as but a slight drag upon the pulleys is sufficient to swing the frames 22 into line with the cables and to cause the pulleys to swing with the cables in other various positions incident to the rise and fall of the boom 13 and the position of the shovel 31.

As the head 28 on the outer end of the boom 13 carries the pin 30 in an offset position, the pulley 23 is held at one side of the boom and above the end thereof so that the cable 32 at all times clears the head 28 and the adjacent parts whether the boom is raised or lowered.

The provision of the head 28 and the counterweighted pulleys on the head and on the out rigger 20 permits of not only the vertical adjustments of the boom but also its extension and its swinging transversely of the frame so that the shovel 31 may be operated back and forth through various distances and at desired angles in front of the work frame 10.

I do not wish to be restricted to the size,

form, and proportions of the various parts, and obviously changes could be made in the construction herein described without departing from the spirit of the invention, it being only necessary that such changes fall within the scope of the appended claims.

What is claimed is:—

1. In a trench filling machine having an out rigger, a boom, a shovel, and cables connected to the opposite ends of the shovel, a counterweighted pulley on the outer end of the out rigger for receiving one of said cables thereover, a head on the outer end of the boom having an offset pin thereon, and a second counterweighted pulley pivotally mounted on said pin and adapted to receive the other cable thereover.

2. In a trench filling machine, provided with a boom and a cable adapted to be supported on the outer end of the boom a head carried by said boom and extending upwardly and laterally from the outer end of the boom, an outwardly projecting pin mounted on the head in offset relation to the boom and a counterweighted pulley mounted on said pin adapted to swing in front of said head and adapted to receive said cable thereover.

3. In a trench filling machine having a stationary out rigger, an adjustable boom, a shovel, and cables connected to opposite ends of the shovel and adapted to be supported upon the outer ends of the out rigger and the boom, a pivot pin projecting from the end of the out rigger, an offset head mounted on the outer end of the boom, a pin projecting outwardly from the head in offset relation to the boom, and counterweighted pulleys pivotally mounted on said pins adapted to receive said cables thereover.

In testimony whereof, we have affixed our signatures in presence of two witnesses.

WALTER G. HUMPHREYS.
OMAR R. HUMPHREYS.
